Inventor:

Frederick E. Dayes

By his Attorney

J. H. Gibbs

UNITED STATES PATENT OFFICE.

FREDERICK E. DAYES, OF BROOKLYN, NEW YORK, ASSIGNEE TO AMERICAN CAR AND FOUNDRY COMPANY, OF NEW YORK, N. Y., A CORPORATION OF NEW JERSEY.

DISK WHEEL.

Application filed March 28, 1922. Serial No. 547,513.

To all whom it may concern:

Be it known that I, FREDERICK E. DAYES, residing at Brooklyn, Kings County, State of New York, and being a citizen of the United States, have invented certain new and useful Improvements in Disk Wheels, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

20 Fig. 1 is an elevational view of one-half of an automobile wheel formed in accordance with the present invention, with a portion thereof broken away for the purpose of detail illustration;

25 Fig. 2 is a vertical sectional view, the section being taken on line 2—2 of Fig. 1;

Fig. 3 is a fragmentary sectional view of a slight modification of the structure illustrated in detail of Fig. 2;

30 Fig. 4 is a view, similar to Fig. 1 of a modified form of my device; and

Fig. 5 is a section taken on the line 5—5 of Fig. 4.

This invention relates to a wheel formed of pressed metal, especially adapted for use on automobiles and motor vehicles, generally.

The principal object of the invention is to provide a wheel of rugged construction, capable of withstanding unusual stresses with a minimum of metal so disposed as to produce the best results.

The parts of the complete structure forming the present invention are capable of being formed with dies, and practically without machine work, and are so shaped that the parts of the complete wheel may be assembled by relatively unskilled labor.

The wheel itself consists of a major disk and a minor disk, to the former of which the felloe is attached, and these parts are so shaped that the major disk may be formed from a sheet of metal of uniform thickness throughout its area, or from a disk, the thick-

ness of which gradually diminishes from its center to its circumference. The minor disk or pan shaped member hereinafter referred to may be of greater or less area and the felloe may be of heavier, thicker, and stronger metal than the other sheet metal parts of the wheel.

It is one of the objects of the invention to produce a wheel of the sheet metal disk type, which may be used with hubs of standard construction, which latter form no part of the present invention.

It is to be noted that the hub A is provided with radial flanges B and C, and in the assembled wheel next the flange B is a disk 4, which is provided with an inturned flange 5 paralleling the portion 6 of the hub, against which the flange 7 of the disk 20 is positioned.

It has been found in some instances that, on account of transmitting tire loads through over-hung and deformed parts of disks in disk wheels, cracks have developed at the point of the bend of the metal, this occurring after considerable service due to fatigue of the metal, and to avoid this I have provided the disk 4 at convenient intervals near its perimeter with a series of depressions 10, whereby shoulders 11 are provided, against or in contact with which shoulders, the felloe 12 of the wheel is supported, as best shown in Fig. 2.

Intermediate the pads or depressions 10, the metal of the disk 4 is bent at substantially right angles to the general plane of the wheel, as shown at 13 in Fig. 2, and this metal is slightly offset as shown at 14 at the lower side of said Fig. 2.

The felloe 12 rests between the shoulder 11 and the flange 15 at said pads and may be secured in position by the rivets 16, which rivets would be in double shear, or the felloe may be secured to the flanges of the disk 4 by spot welding if desired.

To stiffen and reinforce the disk 4 I provide a pan-like disk 20 flanged at 21 in parallelism with the curve of the disk 4 and there secured by rivets 22 or other convenient securing means as may be desired. Interposed between the disks 4 and the minor disks or pan-like reinforcements 20 are pressed steel spacers 23 composed of symmetrical halves, welded or otherwise secured together. These spacers are prefer-

ably formed of sheet metal and are perforated, as are the disks 4 and 20, for the passage therethrough of the securing bolts 25, which connect the disk portion of the wheel 5 with the hub A.

In the drawings, the rear wheel of an automobile is illustrated, which wheel is as usual provided with a brake drum 27, which brake drum is held in position by the bolts 10 25, before referred to.

It is an advantage in disk wheel construction that the disks be so shaped as to permit access from the exterior of the wheel to the tire valve 34, which indicates the conventional valve in common use, and where the pads 10 are pressed in the disk 4, the horizontal flange of the disk and the felloe may be perforated for the passage of said valve 34 therethrough, thus affording convenient accessibility from the outer side of the wheel. Thus, where the depressions or pockets 10 are equidistantly spaced, a great advantage results to the user.

With the construction shown a rim seat 25 can be employed of a desirable thickness without proportionately increasing the weight of the wheel, as with the aid of the pressed pads or pockets a light main disk 4 can be used, at the same time getting the 30 fastening rivets in double shear.

Forming the sheet metal portion of the wheel as indicated permits the use of any desired thickness of metal for either one of the major parts of the wheel and permits 35 a greater range of variety in production than if the disk 4 formed an integral part of the felloe.

The tire may be secured in any desired manner, but preferably is held in position 40 by the bolts 30, which pass through the flange 31, through the spacing members 32 and through the wedge ring 33, and if desired the bolts 30 may be permanently secured in position and the spacers 32 may 45 be electrically welded to the flange 13 to secure them in position, or any convenient means of fastening may be employed.

Instead of having the felloe disposed, as shown, the flange 13 may be modified as 50 shown at 13^a in Fig. 3 and the felloe band 12^a may be employed and provided with the looped portion 12^b, the whole being connected together by rivets 16^a if desired.

In the modified wheel structure shown in 55 Figs. 4 and 5, the main disk 4 and reinforcing disk 20 are provided with the in-turned flanges 5 and 7 engaging the hub portion 6 and the pressed steel spacers 23 are placed between the disks 4 and 20 and 60 held in position by the securing bolts 25 which pass through the hub flanges B and C, disks 4 and 20, spacers 23 and brake drum 27. Near its perimeter, the disk 4 is provided with the spaced depressions 10 65 and the metal of the disk is bent to form a

flange at substantially right angles to the vertical axis of the wheel, as at 13 in Fig. 5, and, at the depressions 10, engages with the shoulders 11 formed by the depressions 10 and is secured thereto by the rivets 16. 70 The free edge of the flange is bent to form a felloe 12' integral with the disk 4. The tire carrying rim is secured to the felloe 12' by the bolts 30 and wedge ring 33, spacing members 32 being secured to the disk 4 if 75 desired. Openings are provided in the metal of a shoulder 11 and the flange for the usual tire valve 34.

What I claim is:

1. In a disk wheel, a main disk, a smaller 80 re-enforcing disk secured thereto and spacing members between said main and re-enforcing disks, said spacing members comprising annular flanged members having depressions therein forming annular engaging surfaces.

2. In a disk wheel, a main disk flanged to engage the hub, a flanged reenforcing disk secured to said main disk and spacing members between said disks having flanges 90 engaged between said disk flanges.

3. In a disk wheel, a flanged main disk, a flanged reinforcing disk and flanged spacing members between said disks, flanges of 95 said spacing members engaging between flanges of said disks.

4. In a disk wheel, a main disk having a web portion and a flanged portion bent to one side of the web portion and crossing the plane of impact of the wheel, and a reenforcing disk secured to the same side of the web portion, said main disk having depressions in said web portion forming supports for said flange portion, projecting 100 from the opposite side of said web and underlying said flanged portion. 105

5. In a disk wheel, a disk having a web portion and a flange portion crossing the plane of impact of the wheel, said web portion having depressions underlying and 110 forming supporting walls for said flange portion, said walls being substantially perpendicular to said flange portion and to the plane of impact.

6. In a disk wheel, a disk having a web 115 portion and a flange portion substantially perpendicular to the wheel plane, said web portion having portions depressed so as to form supports underlying the flange portion.

7. In a disk wheel, a disk having a web portion and a flange portion substantially perpendicular to the wheel plane, said web portion having spaced depressed portions forming supporting shoulders underlying 125 the flange portion, said web and flange portions having valve openings at one of said depressed portions.

8. In a disk wheel, a disk having a web portion and a flange portion substantially 130

perpendicular to the wheel plane, depressed portions in the web adapted to underlie and support the flange portion and a felloe carried by said depressed and flange portions.

5 9. In a disk wheel, a main disk having a web portion and a flange portion bent to cross the plane of impact of the wheel, said main disk having depressions projecting from said web portion and underlying said flange portion to form supports therefor.

10. In a disk wheel, a disk having a web portion and a flange portion substantially perpendicular to the wheel plane, depressions in said web portion underlying said

15 flange portion, a felloe engaging between said flange portion and walls of said depressions and means securing said flange

portion, felloe and said depression walls together.

11. In a disk wheel, a disk having a web 20 portion and a flange portion substantially perpendicular to the wheel plane, depressions in said web portions having walls substantially perpendicular to the wheel plane and connected by walls underlying said 25 flange portion and a felloe secured in position between said flange portion and said depression walls.

In witness whereof I have hereunto set my hand in the presence of two witnesses.

FREDERICK E. DAYES.
